(57) **CLAIM**

The ornamental design for a mesh chef's pan, as shown and described.

DESCRIPTION

FIG. 1 is an isometric view of our mesh chef's pan thereof. FIG. 2 is an isometric exploded view thereof.

FIG. 3 is an isometric exploded view of a lower portion thereof shown separately for clarity of illustration.

FIG. 4 is a isometric view of the lower portion thereof shown separately for clarity of illustration.

FIG. 5 is a top view of the lower portion thereof shown separately for clarity of illustration.

FIG. 6 is a side view of the lower portion thereof with the opposing side view being a mirror image thereof shown separately for clarity of illustration.

FIG. 7 is a top view thereof.

FIG. 8 is a side view thereof, with the opposing side view being a mirror image thereof.

FIG. 9 is an isometric exploded view of an upper or lid portion thereof shown separately for clarity of illustration.

FIG. 10 is an isometric view of the upper or lid portion thereof shown separately for clarity of illustration.

FIG. 11 is an enlarged side cutaway detail view of the lower portion thereof; and,

FIG. 12 is a bottom view thereof.

The broken lines shown in the drawings are for illustrative purposes only and form no part of the claimed design.
